ABSTRACT

An elongated burner body having a series of fuel ports extending along the axis of the burner body is provided with a crossover fuel aperture adjacent the fuel inlet end of the burner. A crossover body comprising a hollow transversely extending member is provided with a crossover fuel inlet aperture from the downstream edge of which extends a depending scoop element. The crossover body is assembled on the burner body so that the crossover fuel apertures are in registration with each other. The scoop serves as a means for locating the crossover body with respect to the burner body and to direct fuel from the burner into the crossover. The scoop element is provided with an opening which allows a portion of the fuel mixture to pass through the opening to directly supply gas to the burner fuel ports most closely adjacent to the crossover and thereby to provide a dependable source of fuel for smooth ignition by the crossover.

FUEL BURNER CROSSOVER ARRANGEMENT

BACKGROUND OF THE INVENTION

This invention relates to fuel burners and more particularly to an improved crossover arrangement for ignition of adjacent fuel burners.

For safety reasons, it is desirable that the ignition of any one burner in a plurality of burners cause rapid ignition of the remaining burners. Such an arrangement is also desirable because it permits the fuel burning apparatus to be ignited with a single pilot. It is, therefore, common practice to provide a transverse fuel passage between adjacent burners which is known as a crossover. The crossover is disposed adjacent a similar crossover of an adjacent burner and is provided with a transverse fuel port. A pilot assembly is located for igniting the fuel discharged from the crossover port of one of the crossovers. When the first crossover is ignited, the flame spreads to ignite its associated fuel burner and the adjacent crossover ports which, in turn, ignite their associated burners.

Difficulties have been experienced with prior crossover arrangements in dependably and smoothly igniting their associated burners due to the crossover tending to interfere with fuel flow to the closely adjacent portion of the burner fuel ports. If the fuel ports adjacent the crossover member are starved for fuel, ignition of its associated burner becomes unreliable and slow. In extreme cases, an explosion hazard may be encountered due to excessive gas being discharged into the combustion chamber before the burner ignites.

SUMMARY OF THE INVENTION

In accordance with this invention, there is provided a burner for a fuel mixture having a generally elongated burner body with suitable port means such as a series of slots or louvers for discharging fuel to be burned along a substantial portion of the axial length of the burner body. A crossover fuel aperture is formed in the burner body adjacent the fuel inlet end. A crossover body having a generally transverse passage is formed with a corresponding crossover fuel inlet aperture. A depending scoop element extends from the downstream edge of the fuel aperture in the crossover body to deflect fuel from the burner body into the crossover. In addition, the scoop serves as a locating means for assembling the crossover body on the burner body and effectively forms a seal with the burner body to inhibit the escape of fuel from between the burner and the crossover.

An aperture is formed in the scoop element to permit a portion of fuel gas to bypass the scoop and flow directly to the burner fuel ports adjacent the crossover body to insure an adequate supply of fuel to the adjacent burner ports for dependable lighting of the burner.

BRIEF DESCRIPTION OF THE DRAWINGS

FIG. 1 is an isometric view of a fuel burner assembly illustrating one of the burners and crossovers in exploded fashion;

FIG. 2 is a cross section through an assembled burner and crossover; and

FIG. 3 is an enlarged perspective view of the underside of the bottom member of the crossover.

DESCRIPTION OF THE PREFERRED EMBODIMENT

Fuel burner assembly 10 is illustrated as including a plurality of generally cylindrical, elongated fuel burner bodies secured with respect to a gas manifold 11 which is provided with a plurality of spaced gas orifices 12 and a corresponding mounting stud 13 adjacent each gas orifice. Burner bodies 16, 17, 18 are provided with burner fuel ports 19 which extend along a substantial portion of the axial length of the burner bodies. Fuel ports 19 in the illustrated embodiment comprise a plurality of transverse slots or louvers centrally disposed across the top side of a generally cylindrical burner body, although it will be appreciated that any type of fuel porting such as one or more axial slots may be employed.

Burner body 18, one of which is shown in exploded fashion in FIG. 1 to better illustrate its relation with the crossover member, is provided with a gas inlet opening 20 adjacent the forward or upstream end thereof which is positioned adjacent and in coaxial alignment with gas orifice 12. Body 18 comprises top and bottom members which are crimped or welded together at their edges. Suitable air inlet openings 21 and 22 are provided so that the stream of gas injected into the hollow interior of the burner body induces ambient air, referred to as primary air, into the interior of the burner body where it mixes with the gas to form a fuel mixture. The air and gas inlet openings, which form the fuel inlet opening, as well as the burner body and mounting arrangement, may take any desired form. In the illustrated embodiment, an axial slot 23, extending from air inlet 21, serves as a locating means for the burner body on manifold 11. The burner body is assembled on the manifold by tilting the body upwardly, inserting mounting stud 13 into air inlet 21, and allowing the burner body to rotate down around the manifold until mounting stud 13 enters slot 23. The arcuate portions 24 at the inlet end of the burner body engage the cylindrical exterior of the manifold so that the open end of the burner is assembled in accurate coaxial registration with gas orifice 12. A suitable air flow control means 25 may be provided to control the amount of primary air induced in the burner, thereby adjusting the fuel mixture of gas and air supplied to the burners. A burner crossover outlet fuel aperture 27 is formed in the top side of the top member of body 18 and is axially located between fuel ports 19 and the end of the burner body adjacent manifold 11.

A crossover body or member 30 which comprises a generally transverse fuel passage is provided on each burner body for ignition of adjacent fuel burners. In the embodiment illustrated, the crossover is formed of a pair of sheet metal stampings which include a top member 31 and a bottom member 32. Top member 31 has a downwardly protruding dimple 34 and an upwardly expanded portion 35. The bottom portion of the crossover member 32 has a downwardly expanded portion 36. When top member 31 is assembled with bottom member 32, a generally transverse hollow fuel passage is formed in the crossover body. Dimple 34 rests on the flat peripheral rearward edge of bottom member 32 so that the forward and side edges of the top and bottom members are spaced to form a cros-

sover fuel port 33 along the entire rearward edges of crossover 30. The top and bottom members of the crossover member are secured to each other by suitable means such as spot welds 37. The transverse fuel passage in crossover 30 of the preferred embodiment is shaped so as to provide a tapering fuel passage as illustrated in the drawings in order to equalize the gas pressure and provide an even length of flame along the entire rearward edge of the crossover when ignited. The arrangement illustrated provides a very simple two-piece crossover member which requires only two stampings and a spot welding operation to complete. However, it will be appreciated that other types of crossover bodies may be employed if desired.

In accordance with this invention, bottom member 32 of the crossover member is formed with a crossover fuel inlet aperture 39. A scoop element 40 extends axially forwardly and downwardly from the downstream or rearward edge of bottom member 32. As illustrated in the drawing, scoop element 40 is preferably formed by a pair of tabs 41 and 42 which are split and slightly spread along their axis to form a central aperture or slot 43 in axial alignment with the crossover and burner bodies. Crossover fuel inlet opening 39 and scoop 40 are preferably formed simultaneously during the stamping operation which forms bottom member 32 by simply stamping a downwardly extending pair of tabs from the parent metal of member 32. Scoop element 40 preferably has a spherically contoured shape with a substantially triangular shaped opening defined by the spaced edges of the tabs forming the scoop element and defines a rectangular or semicircular crossover fuel inlet aperture in crossover body 30.

The two members 31, 32 forming the crossover body are first secured to each other by some suitable means such as spot welds 37. The crossover member 30 is then positioned on top of burner body 18 with scoop element 40 extending downwardly into the hollow burner body through crossover fuel aperture 27. The distance between the transverse edges of scoop element 40 at their junction with the bottom of crossover body 30 is substantially the same as the transverse dimension of aperture 27 and the axial dimension of aperture 39 may be substantially the same as the axial dimension of aperture 27 so that scoop 40 forms a locating means for crossover 30 on the burner. Consequently, the crossover member is accurately aligned in the desired position on the burner body without the need of fixtures or other locating means. The flange portions 45 of crossover 30 are then secured to flange 46 on the burner body by suitable means such as spot welds 38.

In operation, a plurality of assembled burner bodies and crossover members are positioned in spaced relation along gas manifold 11. A suitable pilot assembly 50 is disposed adjacent at least one of the crossover members so that the pilot flame can impinge on fuel port 33 of the crossover. When gas is supplied from the manifold into the burner bodies, a portion of the fuel mixture is passed upwardly into the crossovers and discharged into the region of the pilot flame. The pilot ignites the fuel discharged from the crossover and spreads transversely from crossover to crossover until each of the crossovers is ignited. At the same time when the flame reaches the rear edge of the crossover, it ignites fuel discharged from the fuel ports in 19 ad-

jacent the crossover. Aperture 43 in the scoop elements allows fuel to pass directly through the scoop element aperture to the fuel ports 19 most closely adjacent the rear edge of the crossover. Consequently, the scoop does not excessively reduce the supply of fuel to the portion of the burner ports adjacent the crossover port so that rapid and highly reliable ignition of the burners is achieved.

It will be seen that by providing a crossover with a scoop element in accordance with this invention, the speed and reliability of the main burner ignition is improved while, at the same time, the scoop element serves as a locating means for the crossover during manufacture and as a seal to reduce escape of fuel from between the burner body and crossover member.

While a preferred embodiment of this invention has been described for purposes of illustration, it will be appreciated that this invention may be otherwise embodied within the scope of the following claims.

I claim:

1. A gas burner comprising an elongated hollow gas burner body having fuel inlet opening means adjacent one end thereof, said burner body having fuel burner port means extending along the top side thereof for discharging said fuel mixture along a substantial portion of the axial length of said burner body, a crossover fuel aperture formed in the top side of said burner body between said one end of said burner body and the other end thereof; a crossover body mounted on said burner body, said crossover body being hollow and forming a crossover fuel passage extending transversely of said burner body, said crossover body defining crossover fuel port means having a portion thereof disposed adjacent the fuel burner port means in said burner body and extending transversely therefrom, said crossover body having a crossover fuel inlet aperture formed on the bottom side thereof disposed in registration with said crossover fuel aperture on the top side of said burner body, and a crossover scoop element extending downwardly from the downstream edge of the crossover fuel aperture in the crossover body through the crossover fuel aperture in the burner body into the interior thereof to deflect a portion of fuel mixture from the interior of said burner body into said crossover body for passage through said crossover fuel port means, said crossover scoop element having an opening formed therein to allow another portion of the fuel mixture to pass from said one end of said burner body through said opening in the scoop element to a portion of the fuel burner port means in the burner body located adjacent the crossover fuel port means of said crossover body.

2. A gas burner as defined in claim 1, wherein said opening in the scoop element comprises a centrally disposed slot.

3. A gas burner as defined in claim 1, wherein said scoop element comprises a pair of tabs extending downwardly from the bottom of said crossover body, said opening in the scoop element comprising a slot between said tabs.

4. A gas burner as defined in claim 1, wherein said crossover scoop element has a transverse dimension substantially the same as the transverse dimension of the crossover fuel aperture in said burner body so that the scoop element serves as a locating means for said

crossover body on said burner body and as a sealing means between said crossover and burner bodies.

5. A gas burner comprising an elongated hollow gas burner body having fuel inlet opening means adjacent one end thereof, said burner body having fuel burner port means extending along the top side thereof for discharging a fuel mixture along a substantial portion of the axial length of said burner body, a crossover fuel aperture formed in the top of side of said burner body between said one end of said burner body and the other end thereof; a crossover body mounted on said burner body, said crossover body being hollow and forming a crossover fuel passage extending transversely of said burner body, said crossover body defining crossover fuel port means having a portion thereof disposed adjacent the fuel burner port means in said burner body and extending transversely therefrom, said crossover body having a crossover fuel inlet aperture formed on the bottom side thereof disposed in registration with said crossover fuel aperture on the top side of said burner body, and a crossover scoop element extending

downwardly from the downstream edge of the crossover fuel aperture in the crossover body through the crossover fuel aperture in the burner body into the interior thereof to deflect a portion of fuel mixture from the interior of said burner body into said crossover body for passage through said crossover fuel port means, said crossover scoop element having a transverse dimension substantially the same as the transverse dimension of the crossover fuel aperture in the burner body so that the scoop element serves as a locating means for assembling the crossover body on the burner body during assembly thereof.

6. A gas burner as defined in claim 5, wherein said crossover scoop element has an opening formed therein to allow another portion of the fuel mixture to pass from said one end of the burner body through said opening in the scoop element to a portion of the fuel burner port means in the burner body located adjacent the crossover fuel port means of the crossover body.
